REINFORCING MEANS FOR CONCRETE.

1,000,519.

Specification of Letters Patent. Patented Aug. 15, 1911.

Application filed December 20, 1909. Serial No. 534,901.

To all whom it may concern:

Be it known that I, JOHN F. HAVEMEYER, a citizen of the United States, and a resident of Ardsley-on-Hudson, in the county of Westchester and State of New York, have invented an Improvement in Reinforcing Means for Concrete, of which the following description, in connection with the accompanying drawings, is a specification, like figures on the drawings representing like parts.

This invention relates to reinforcing means intended to be embedded in concrete or the like to contribute to the strength of the composite structure.

Among other objects, the invention is designed to provide a reinforcing bar suitably deformed to afford effective bonds to engage the concrete which shall be economical to manufacture and have uniform cross sectional area throughout such part of its length as may be desired.

The character of the invention may be best understood by reference to an illustrative embodiment shown in the accompanying drawings in which:

Figure 1 is a perspective of an illustrative bar; Fig. 2 is a section on the cross-sectional plane of line 2—2 of Fig. 1; and Fig. 3 is a similar section on the cross-sectional plane of line 3—3 of Fig. 1.

The exemplary bar shown in the drawings is substantially square in its main cross-section, but a bar embodying the features of this invention may have any desired or practicable cross-sectional shape. On each face of the illustrative square bar, is provided a longitudinally aligned series of shuttle shaped projections 5—5, or 6—6. These projections in each series are preferably spaced at equal distances lengthwise of the bar.

Each projection is preferred to be formed by only slightly distorted fibers of the bar having as gradual an inclination to the surface of the bar as practicable in order to preserve a maximum efficiency of the fibers, a substantial part of which is lost in those bars in which the distortions are abrupt as in a bar having projections the ends of which are substantially perpendicular to the surface of the bar. While the shuttle-shaped projections described, with the minimum distortion of the material which they require, is preferred, certain features of the

invention may be employed with projections or other distortions of any practicable form or shape.

As shown in Fig. 1, the projections 5—5 on one face of the bar are staggered in relation to the projections 6—6 on an adjacent side, so that each projection of one series is positioned, transversely of the bar, opposite a depression intervening between adjacent projections of the other series. Also the opposite ends of each projection 5 overlap adjacent ends of two projections 6—6. With this arrangement a cross-sectional plane passed through the line 3—3 of Fig. 1 intersects a projection 5 and also a projection 6 as shown in Fig. 3, so that the sum of the intersected area of projection 5 plus the intersected area of projection 6 enters into the total cross-sectional area of the bar at that point. In order to preserve a uniform cross-sectional area for the bar throughout its length, the projections are preferably tapered at their ends so that the sum of the cross-sections of a projection 5 and a projection 6 intersected by any cross-sectional plane which cuts through both projections, shall equal the maximum cross-sectional area of any projection. That is to say, in the cross-section shown in Fig. 3 the included area of the projection 5 plus the included area of the projection 6, exactly equals the maximum area of the projection 6 in the section shown in Fig. 2. In Fig. 2, it will be observed that no part of the projection 5 enters into the cross-sectional area of the bar as a whole. It is evident, therefore, that the projections lying wholly at one side of an axial plane on the line 8—8 of Figs. 2 and 3, contribute either singly or together to an entirely uniform cross-section of the bar independently of any projections or other deformation which may occur on the bar at the opposite side of said axial plane. It is entirely practicable, therefore, to have the bar made with projections 5—5 and 6—6 on only two of its faces, the other faces being left, if desired, smooth and undisturbed. If preferred, however, each half of the bar on each opposite side of the axial plane may be provided with a plurality of series of projections arranged in the manner described, and it will be obvious that there will have to be an even number of series on each half.

It is preferred that the surface of the

bar, where intersected by the axial plane on the line 8—8, be substantially undisturbed by deformation. The purpose of this is to avoid the necessity for having any part of the bar deformed by the conjoint operation of coöperating rolls. In some types of bars heretofore attempted to be made, the entire surface of the bar has been in some degree distorted, requiring the two opposite rolls by which the bar is formed, to have mating or intermeshing parts at adjacent portions of the rolls; but whenever such rolls become slightly offset, as is practically unavoidable, the mating or intermeshing parts would cease to coöperate properly with the result that the bar would be incorrectly rolled and uniformity of cross-sectional area would be destroyed. All such difficulties are avoided in the construction of the bar shown in the drawings in which adjacent parts of the rolls coöperate to form only the undisturbed, preferably rounded corners, intersected in Figs. 2 and 3 by the line 8—8. However the projections are disposed, it is preferred that they fulfil the requirement above described that all of the deformations lying wholly at one side of an axial plane, contribute uniformly to the cross-sectional area of the bar.

As shown, the projections 5—5 and 6—6 have their greatest dimensions substantially parallel with the length of the bar. While this is preferred it is not indispensable. The form of shuttle-shaped projection illustrated is desirable both because of the slight necessary distortion of the fibers of the bar, and because the forming groove required to be made in the roll is very easy to make.

It is to be understood that this invention is not limited to the specific embodiment described above and shown in the drawings for illustration. On the contrary the invention may be variously embodied within the scope of the subjoined claims.

Claims.

1. A reinforcing bar having four faces and a single longitudinal row of separated projections on at least each of two adjacent faces the said projections being of less width than the face of the bar on which they are placed, the surface of the bar between said projections being plane, the projections on one face being staggered in relation to those on the adjacent face and overlapping at such point longitudinally of the bar as to maintain a constant cross sectional area. 50
2. A reinforcing bar of any uniform cross section having longitudinal rows of separated projections, the said rows being substantially ninety degrees apart around the circumference of the bar and the width of each projection transversely of the bar being less than one quarter of the circumference of the bar, the projections in each row being staggered with relation to those in an adjacent row and being so proportioned as to preserve a constant cross-sectional area and the surface of the bar between said projections being plane. 60
3. A reinforcing bar of any uniform section having longitudinal rows of separated projections, the said rows being substantially ninety degrees apart around the circumference of the bar and the width of each projection transversely of the bar being less than one quarter of the circumference of the bar, and the projections in each row being staggered with relation to those in an adjacent row and being so proportioned as to preserve a constant cross-sectional area. 70

In testimony whereof, I have signed my name to this specification, in the presence of two subscribing witnesses.

JOHN F. HAVEMEYER.
